UNITED STATES PATENT OFFICE.

EARL G. WATROUS, OF CHICAGO, ILLINOIS.

LAVATORY-FIXTURE.

1,108,956.

Specification of Letters Patent.

Patented Sept. 1, 1914.

Application filed July 26, 1909. Serial No. 509,567.

To all whom it may concern:

Be it known that I, EARL G. WATROUS, a citizen of the United States, residing in Chicago, Cook county, Illinois, have invented 5 certain new and useful Improvements in Lavatory-Fixtures, of which the following is a specification.

My invention relates to lavatory fixtures and the object thereof is to provide a simple 10 and compact construction of fixtures particularly for lavatories of the special class or character as used in sleeping cars, for instance in the well known Pullman cars, where such fixtures may not only be compact 15 but also readily accessible and capable of convenient assembling and dis-assembling.

My new fixture has been designed and constructed to overcome previous practical difficulties and to embody the features of ad- 20 vantage above mentioned.

In the drawing, Figure 1 is a sectional elevation of a fixture embodying my invention shown applied to a bowl of the usual construction as used in sleeping cars and the 25 like; Fig. 2 a vertical section of such fixture; Fig. 3 a bottom plan of the arch plate or escutcheon for the operating buttons; and Fig. 4 is top plan thereof.

Referring to the present embodiment of 30 my invention as illustrated in the drawing, my fixture is adapted to be used in connection with any suitable bowl construction such as the bowl 1 which, by means of such fixture, is adapted to be secured or clamped 35 to a suitable support 2 in the manner hereinafter described.

As shown particularly in Fig. 2, the fixture comprises a casing 3 having a cold water pipe connection 4 at one side and a 40 hot water pipe connection 5 at the other side and also having two separate valve chambers 6 and 7, the former of which communicates with the cold water connection and the latter of which communicates with the hot water connection. The inlet from the cold water connection to the valve chamber 6 is had through a port 8 which is governed by a valve having a piston portion 9 directly governing said port and a valve seat portion 50 10 governing a port 11 from said valve chamber to a cross-passage or chamber 12 which is common to both of the valve chambers. This valve is normally held seated with a yielding pressure as by means of the 55 coiled spring 13, thereby closing both ports 8 and 11. The hot water valve chamber and

its valve is similarly constructed, communication being had between the hot water connection and the valve chamber through the port 14 and the valve comprises the piston portion 15 and valve seat portion 16, which latter governs a port 17 from the valve chamber to the common passage or chamber 12, the valve being normally held seated by means of the coiled spring 18. The trans- 65 verse passage or chamber 12 communicates at its central portion with a vertical passage or chamber 19 which in turn communicates with the branch connection 20 communicating at its outer end with the flush nozzle 21 70 arranged on the inner wall of the bowl toward the upper end thereof as clearly indicated in Fig. 1, with the result that the water is delivered upon the side wall of the bowl. For the purpose of operating the 75 valves, the same are provided at their upper ends with operating buttons 24 and 25 respectively which are properly marked to indicate the hot and cold water as shown in Fig. 4. In the present instance these valve 80 stems extend through stuffing boxes composed of the packing nuts 26, packing 27 and lock nuts 26a. In order to provide a bearing for the upper ends of the valve stems and their operating buttons and also 85 to provide a part for the clamping means for securing the parts in place, and also to provide a slightly and finished appearance, the arch plate or escutcheon 28 is employed, the same being provided on its flat or horizontal surface with openings through which the operating buttons project while the more or less vertical or flanged portion thereof rests upon the plate 1a which is here shown as a separate part of the bowl structure, although this is not essential. For the 90 purpose of holding the escutcheon in place and for determining the proper position thereof such escutcheon is provided with depending dowel pins 29 adapted to enter corresponding openings in the plate 1a in the manner shown in Fig. 2. To prevent the operating buttons from rotating and thereby to keep the same in proper position for reading the words "Hot" and "Cold" thereon, 95 the escutcheon is provided with the depending flanges 30 while the lower portion of the operating buttons each have on one side a pair of lugs 31 coöperating with said depending flanges. In practice the operating 100 buttons are made in two pieces, an outer shell portion secured to the valve stems and

a porcelain portion indicated at 24^a and 25^a respectively, to which the words "Hot" and "Cold" are applied.

In order to secure the escutcheon in place and at the same time securely hold and clamp the fixture and the bowl to the support 2, a screw 32 extends through the central portion of such escutcheon and through the plate 1^a and into an extension or base portion 33 of the casing 3 which abuts the under surface of said plate as clearly shown in Fig. 2. The casing 3 is in addition provided with a bracket portion 34 which extends below the support 2 with the result that when the parts are assembled as shown in Figs. 1 and 2 and the screw 32 screwed inwardly, such parts will be firmly secured together and will moreover be rigidly clamped to the support 2 and likewise the bowl structure will be firmly held to the fixture as well as to said support. At the same time the construction is such that the parts may be very readily dis-assembled for any desired purpose; even though, as in the case of the particular use in sleeping cars, the space is limited and access to the fixture more difficult than in ordinary situations. Furthermore, my device is extremely simple and compact with the main portion of the fixture concealed, the only exposed portion, which is made of neat and pleasing appearance, being the operating buttons and the escutcheon.

I claim:

35 1. In a lavatory fixture, the combination, with the bowl and the top plate thereof, of a casing having a water supply connection, valve mechanism therein, a depressible operating rod for the valve mechanism, an arched plate arranged to be secured to said casing and to clamp the top plate of the bowl, and a button connected with said operating rod and passing through and operating in said plate; substantially as described.

2. In a lavatory fixture, the combination, with the bowl and the top plate thereof, of a casing having a water supply connection, valve mechanism therein, a depressible operating rod for the valve mechanism, an arched plate arranged to be secured to said casing and to clamp the top plate of the bowl, and a button connected with said operating rod and passing through and operating in said plate, said arched plate and button having coöperating means for preventing the rotation of the button in the plate.

3. In a lavatory fixture, the combination, 60 with the bowl and the top plate thereof, of a casing having a water supply connection, valve mechanism therein, a depressible operating rod for the valve mechanism, an arched plate arranged to be secured to said casing and to clamp the top plate of the

bowl, and a button connected with said operating rod and passing through and operating in said plate, said button having a bottom flange provided with lugs 31 and the plate having a projection 30 coöperating therewith to prevent rotation of the button in the plate. 70

4. In a lavatory fixture, the combination, with the bowl and its top plate, of a casing having a water supply connection and an extension coöperating with the underside of a portion of the bowl structure, valve mechanism within the casing, a depressible operating rod for the valve mechanism, a plate arranged to be secured to said extension and 75 to clamp the top plate of the bowl and fixture together, and a button passing through the plate and connected with said rod, substantially as described. 80

5. In a lavatory fixture, the combination, 85 with the bowl and its top plate, of a casing having hot and cold water supply connections, valve mechanisms therein for governing the hot and cold water, operating rods for said mechanisms, and a plate secured to 90 said casing and having openings for the operating rods, said two plates having means for interlocking connection; substantially as described.

6. In a lavatory fixture, the combination, 95 with the bowl and its top plate, of a casing having hot and cold water supply connections, valve mechanisms therein for governing the hot and cold water, operating rods for said mechanisms, and a plate secured to 100 said casing and having openings for the operating rods, one of said plates having dowel pins and the other corresponding dowel holes for interlocking connection between such plates. 105

7. In a lavatory fixture, the combination, with the bowl and its top plate, of a casing having hot and cold water supply connections and having a central upward extension, valve mechanisms therein for governing the 110 hot and cold water, operating rods for said mechanisms, an arched plate secured at its middle portion to said extension and having openings in register with said rods, and buttons received in said openings connected 115 with said rods; substantially as described.

8. In a lavatory fixture, the combination, with the bowl and its top plate, of a casing having a substantially central upward extension and hot and cold water supply connections, valve mechanisms in said casing on either side of said extension, parallel and depressible operating rods connected with said valve mechanisms and located on either side of said extension, and a plate having 125 openings for the rods and secured to such extension and thereby held to said top plate.

9. In a lavatory fixture, the combination, with the bowl and its top plate, of a casing having an upward extension 33 in contact 130

with the under side of such plate, such casing having hot and cold water supply connections and a discharge outlet communicating with the bowl, valve mechanisms in 5 said casing, depressible operating rods 22 and 23 for said valve mechanisms respectively, a plate 28 upon said top plate and a screw 32 passing through the plate 28 and engaging such extension for securing the 10 latter plate to the top plate of the bowl, said two plates having registering openings for the operating rods; substantially as described.

10. In a lavatory fixture, the combination, 15 with the bowl and its top plate, of a casing having a water supply connection and an extension coöperating with the underside of a portion of the bowl structure, said casing also having a bracket 34, valve mechanism within the casing, an operating rod for the valve mechanism, and a plate 28 coöperating with said rod and arranged to be secured to the extension and to clamp the top plate of 20 the bowl and fixture upon a fixed support; substantially as described.

1. In a lavatory fixture, the combination, 25 with a bowl and its top plate, of a casing having a water supply connection and an extension coöperating with the underside of 30 a portion of the bowl structure, valve mechanism within the casing, an operating rod for the valve mechanism, and a plate coöperating with said rod and arranged to be secured to said extension and to clamp the 35 top plate of the bowl and casing together;

said plate 28 having dowel pins adapted to engage the top plate of the bowl; substantially as described.

12. In a lavatory fixture, the combination, 40 with the bowl and its top plate, of a casing having hot and cold water supply connections, valve mechanisms therein for governing the hot and cold water, operating rods for said mechanisms, said casing also having a central post or extension whose lower portion has a discharge passage communicating with the bowl and whose upper end bears against the lower surface of the bowl structure, an arched plate 28 located on the top plate of the bowl and arranged to guide the 45 rods, and a screw passing through the central portion of the plate 28 and into the upper end of the post or extension; substantially as described.

13. In a lavatory fixture, the combination, 55 with the bowl and its top plate, of a casing having hot and cold water supply connections at its opposite sides, valve mechanisms therein for governing the water supply, operating rods for said mechanisms, a plate 28 60 located upon and having tongue and slot connection with the top plate of the bowl, and buttons 24 and 25 passing through said plate 28 and connected with said rods; substantially as described.

EARL G. WATROUS.
